UNITED STATES PATENT OFFICE

2,619,374

OVERSHOT

Vernon D. Davidson, Corpus Christi, Tex.

Application February 18, 1949, Serial No. 77,076

1 Claim. (Cl. 294—102)

1

The invention relates to an overshot.

In the drilling of wells by the rotary method it is not uncommon for a drill pipe to twist off or to become stuck in the well bore. It is then necessary to retrieve the pipe from the bore before drilling operations can be resumed.

It is, therefore, an object of the instant invention to provide a tool for engaging and removing a stuck pipe or "fish" in a well bore.

Another object of the invention is to provide an overshot for engaging a stuck pipe in a well bore, which overshot is provided with spring fingers for engaging a tapered area on the stuck fish.

Another object of the invention is to provide in an overshot for engaging a tapered area of a stuck pipe in a well bore spring fingers which are provided with threaded means for engaging the taper on the stuck pipe, the taper of such threaded means being different from the taper on the engaged pipe so that the overshot may be released or disengaged from the stuck pipe by rotation to travel the threaded means up on the threaded area to release the overshot.

Other and further objects and advantages of the invention will become more readily apparent from a consideration of the following description and drawings, wherein:

The figure is a vertical sectional view illustrating a stuck pipe in elevation in a well bore with the overshot portion of the tool engaged on the taper of such stuck pipe;

Generally, when a pipe becomes stuck in a well bore it is preferable to remove the pipe by engaging a tool with the pipe and exerting an upward pull thereon.

The tool comprising a form of the invention is illustrated in the figure and is shown in the figure as comprising a housing 2 with an overshot 3 slidably but non-rotatably mounted therein. To this end there is provided in the housing 2 a bolt 3' engaged in the longitudinal slot 4 of the overshot 3. The lower end 5 of the overshot 3 is provided with a plurality of spring fingers 6. These spring fingers are adapted to expand around the enlarged portion 7 of the pipe as it is being lowered downwardly into the well bore, as indicated by the dotted line at 7'.

Upon contact with the tapered area of a tool joint as illustrated at 9, the fingers 6 spring inwardly, whereupon the threaded means 10 engage with the tapered area 9 on the stuck pipe or fish 11. Upon reaching the desired elevation on the stuck pipe at which it will be attempted to remove such pipe from the well bore, an upward pull may be exerted on the housing 2 to effect relative movement between housing 2 and the overshot 3.

A tapered shoulder 13 in the housing 2 abuts against the taper 14 on the overshot 3, whereupon such overshot becomes seated in the housing 2. A continued upward pull on the housing 2 is transmitted through the overshot to the fish 11, whereupon it may become disengaged and pulled

2

from the well bore. The tapers 13 and 14 cooperate to effect a locking action between the annular threaded means 10 on the inner periphery of the spring finger 6 and the tapered area 9 of the fish.

If, however, for any reason the fish 11 will not dislodge from the well bore, it is desirable to release the overshot therefrom so as to remove the tool from the well. To this end it is to be noted that the taper of the annular threaded means 10 is somewhat different from the taper of the unthreaded area 9. This is more clearly illustrated by the line 15, which shows the taper of the threaded means 10 as being different from the taper on the area 9 of the pipe joint. In this manner when a combined upward pull and rotation is imparted to the housing 2, the threaded means 10 will travel up on the tapered area 9 and eventually release the fingers 6 from engagement with such tapered area. The spring fingers 6 will then expand to conform to the enlarged portion 7 of the tool joint on the stuck pipe 11. The overshot tool may then be removed from the well.

Broadly, the invention contemplates a releasable overshot.

What is claimed is:

A pulling tool for pulling a stuck pipe having a downwardly and inwardly tapered area thereon from a well bore comprising, a housing to telescope over such stuck pipe, an overshot rotatable with said housing and slidable therein, spaced radial elongated spring pulling fingers integrally formed on said overshot, a threaded area internally disposed on the pipe contacting surface of said pulling fingers, said threaded area being of different taper than said tapered area on said stuck pipe and formed to project inwardly relative to the maximum diameter of said tapered area, and inclined surfaces on adjacent portions of said fingers and said housing cooperating so that the upper threads of said pulling fingers engage said tapered area of said stuck pipe to pull said pipe upwardly upon a straight upward pull of said housing, and upon failure of said straight pull the difference of the taper of said threads enabling said overshot to travel on said tapered area of said pipe by a combined upward pull and rotation of said housing.
